UNITED STATES PATENT OFFICE.

ISAAC E. PALMER, OF MIDDLETOWN, CONNECTICUT.

CLAMP FOR TENTERING-MACHINES.

SPECIFICATION forming part of Letters Patent No. 587,753, dated August 10, 1897.

Application filed October 21, 1896. Serial No. 609,501. (No model.)

To all whom it may concern:

Be it known that I, ISAAC E. PALMER, of Middletown, in the county of Middlesex and State of Connecticut, have invented a new and 5 useful Improvement in Clamps for Tentering-Machines, of which the following is a specification.

My invention is an improvement in clamps for tentering-machines, and relates to those 10 machines in which two tentering-wheels are employed, each of said wheels being provided with clamps along its periphery in position to engage the selvage edge of the cloth being treated.

15 The object of my invention is to provide a clamp of the above character which will be thoroughly adjustable, so as to enable the clamp to effectually grip the selvage edge and prevent its slipping or tearing when the clamp 20 is closed and the material is being tentered and allow the material to be quickly inserted or withdrawn when the clamp is open.

A practical embodiment of my invention is 25 represented in the accompanying drawings, in which—

Figure 1 is a side view of a tentering-wheel with a number of the clamps shown in position thereon, it being understood that the clamps in practice extend entirely around the 30 face of the periphery of the said wheel. Fig. 2 is a vertical central section through the wheel on the line 2 2 of Fig. 1. Fig. 3 is a perspective view, considerably enlarged, of one of the clamps, showing it partially opened; 35 and Fig. 4 is a vertical central section of one of the clamps, showing the seat as concave laterally and the adjustable gripping-plate on the swinging jaw having a convex surface.

The tentering-wheel is denoted by A, and 40 it is mounted to rotate in suitable bearings in supports B, one of which supports is provided with a pair of fixed or stationary cams b b', located in proximity to the face of the tentering-wheel in position to engage the tentering-clamps to open them at the proper times.

The clamp as a whole is denoted by C, and it consists of a rigid jaw c, having an adjustable seat c', hinged at c' to the upper end of the said fixed jaw, and a spring-actuated swing- 50 ing jaw c³. The fixed jaw c is further provided with a downwardly-extended portion

c⁴, which is adapted to be secured rigidly to the face of the wheel A. The upper portion of the jaw c is bifurcated, and between its branches is pivoted the swinging jaw c³, the 55 pivot therefor being denoted by c⁵. The said jaw c³ is spring-actuated by means of a suitable spring D, which is in the present instance shown of coiled form wound around the pivot-pin c⁵ and exerting its pressure in a direction 60 to close the swinging jaw c³. The head of the swinging jaw c³ is provided with an adjustable plate c⁶, pivoted to the said jaw at c⁷. The rear or free end of the adjustable support c' is bifurcated for embracing the opposite sides of the swinging jaw c³, and the said swinging jaw is provided with suitable abutments or shoulders c⁸, which are adapted to slide along the under face of the adjustable seat and raise it as the clamp is closed. A 70 retaining-pin c⁹ passes through the jaw c³, above the adjustable seat c', and serves to retain it in engagement with the shoulders c⁸. The adjustable gripping-head of the swinging jaw c³ may or may not be provided with 75 teeth, as may be desired, and the adjustable seat c' also may or may not be provided with teeth, as is found more desirable.

In the form shown in Fig. 4 the seat c' is 80 shown as provided with rearwardly-projected teeth c¹⁰, and the said seat is also shown as concave laterally. The adjustable gripping-head c⁶ at the free end of the swinging jaw c³ is also shown as provided with rearwardly-extended teeth c¹¹, and the said head is convex 85 in such a direction as to substantially fit into the concaved adjustable seat.

The spring-actuated swinging jaw c³ is provided with a suitable tailpiece c¹², which is adapted to be engaged by the fixed cams b b' 90 for opening the clamp at the proper times.

In operation as the tentering-wheel A is rotated the clamps C are first opened by one of the fixed cams for receiving the selvage edge of the material being tentered. The 95 clamps are then closed by the springs D and the material is retained until the wheel has rotated sufficiently to allow the other fixed cam to again open the clamps, when the material may be freely withdrawn therefrom. 100

By reason of the adjustability of the clamping-jaw and the adjustable seat therefor the

material when engaged by the clamp is held absolutely against slipping and tearing and yet may be very readily inserted into or disengaged from the clamp when it is open.

5 It is evident that slight changes might be resorted to in the construction and arrangement of the several parts without departing from the spirit and scope of my invention. Hence I do not wish to limit myself strictly 10 to the structure herein set forth; but

What I claim is—

1. A clamp for tenting-machines comprising a rigid jaw and a swinging jaw arranged to coact therewith, the one being provided 15 with an adjustable seat and the other with an adjustable gripping-plate, substantially as set forth.

2. A clamp for tenting-machines, comprising a rigid jaw, an adjustable seat pivoted 20 thereon, a spring-actuated swinging jaw pivoted to the fixed jaw and an adjustable gripping-plate pivoted to the swinging jaw in position to grip the material between it and the

adjustable seat when the clamp is closed, substantially as set forth. 25

3. A clamp for tenting-machines, comprising a rigid jaw, an adjustable seat pivoted at one end to the fixed jaw and having rearwardly-extended branches, a swinging jaw pivoted to the fixed jaw and adapted to reciprocate between the said branches of the adjustable seat, abutments on the swinging jaw for guiding the movement of the adjustable seat and a gripping-plate carried by the swinging jaw, substantially as set forth. 30

4. A clamp for tenting-machines, comprising a rigid jaw, an adjustable seat concaved laterally pivoted to the fixed jaw, a swinging jaw pivoted to the fixed jaw and a gripping-plate convexed laterally secured to the swinging jaw, substantially as set forth. 35 40

ISAAC E. PALMER.
